UNITED STATES PATENT OFFICE

EDWARD M. OWENS, OF DALLAS, TEXAS

GARBAGE INCINERATOR

Application filed January 20, 1928. Serial No. 248,080.

The present invention consists of a garbage incinerator constructed to cremate the garbage in an expeditious manner by selectively charging or feeding the wet and dry garbage into different parts of the incinerator.

Another object of the invention is to provide an incinerator which is equipped with a water jacketed chute which prevents warping or distortion of the chute due to the intense heat in the incinerator into which the chute projects.

A further object of the invention is to provide a water grate, for the reception of wet garbage, which is in communication with a water jacketed chute to constantly circulate water through the grate and chute to effect a water cooling system.

A still further object of the invention is to provide superposed grates for wet and dry garbage respectively, which overhangs an ash deflector through the medium of which ashes are deposited directly on a conveyor belt to prevent accumulation of hot ashes and correspondingly to eliminate premature deterioration of the grate by the heat from the ashes.

A still further object of the invention is to provide grates which are arranged in superposed relation in the incinerator housing to which the garbage is fed through a convertible chute, the latter being capable of rapid adjustment to permit depositing garbage on either one of the grates at the option of the user.

Other objects of the invention will be apparent from the following description of the present preferred form of the invention, taken in connection with the accompanying drawings, wherein

Figure 1 is a fragmentary side elevational view of an incinerator constructed in accordance with the present invention, illustrating its application.

Figure 2 is a vertical sectional view of the same;

Figure 3 is a detail fragmentary side elevational view of a housing through which the garbage is introduced into the incinerator, showing to advantage the counterbalanced door closing communication through the garbage opening;

Figure 4 is a transverse sectional view taken through the incinerator above the wet grate and water jacketed chute;

Figure 5 is a detail enlarged fragmentary sectional view of the water jacketed chute; and,

Figure 6 is a detail fragmentary vertical sectional view of the water tank used in the present invention.

The device of the present invention embodies a housing, generally designated 7, which is made of concrete or any other suitable fire-proof material and is equipped with a charging or feeding floor 8. One wall of the housing is provided with an opening 9 which opens to the charging floor and through which garbage is adapted to be passed into the incinerator in a manner hereinafter explained. The opening is normally closed through the medium of a counterbalanced door 10, mounted on the inside of the housing wall as illustrated to advantage in Figure 3. Although a single opening 9 is shown, it is of course to be understood that a series of openings may be provided if desired, corresponding to the number of incinerators which are to be used.

The incinerator per se consists of a casing or housing 11 which is preferably made of concrete or other plastic fire-proof material and may be of any desired size and configuration. The casing is provided in the side adjacent the housing 7 with an opening, the wall of which is covered by a metal frame 12. A portion of the incinerator casing opening is in alignment with the opening 9 of the housing 7, while the remainder of the opening extends appreciably below the opening 9 and is adapted for the reception of one end of a chute 13. The chute 13 has its upper end impinged against the outside wall of the housing 7 below the opening 9 and tapers inwardly toward its opposite end, the latter projecting through the casing 11 of the incinerator. The chute is provided with a hollow bottom and hollow sides 14, in order to provide a water space, thereby providing a water jacket for the entire chute. The water jacket in the bottom of the chute is provided with a series of baffles 15, which are preferably arranged

in staggered relation, as shown in Figure 4 of the drawings, so that the water in passing through the jacket will follow a tortuous passage-way.

- 5 Upon reference to Figure 2 of the drawings, it will be noted that the thickness of the casing 11 is reduced from a point near the bottom of the casing upwardly toward the top of the latter, the juncture of the reduced part 10 of the casing with the bottom of the latter providing a base which receives the marginal edge of an ash deflector 16 hereinafter described, upon which is superimposed a fire wall 17. The fire wall is concentrically 15 mounted in the casing 11 and is preferably made of fire brick in order to withstand the intense heat generated by the burning of the garbage. Furthermore, the fire wall is spaced from the casing to provide an air 20 passage-way 18 for an obvious purpose. The upper end of the fire wall is reduced to provide an annular shoulder which supports a truncated cone shaped draft collar 19, which latter is also preferably made of fire brick 25 and prevents down draft through the incinerator, in addition to preventing gases from escaping from the incinerator until they are completely consumed.

Mounted in the fire wall 17 near the bottom 30 of the latter and directly above the ash deflector 16 is a grate 20 of standard construction which is adapted for the reception of dry garbage and is arranged in the path of the chute 13, so that garbage deposited on the 35 latter will gravitate directly on to the grate. A wet grate 21 is superposed above the grate 20 and is adapted for the reception of wet garbage. The grate 21 is preferably composed of a series of tubes, the terminals of 40 which communicate with conduits 22, one of which is arranged in proximity to the chute 13 and has a pipe 23 leading therefrom which communicates with the water jacket in the bottom of the chute 13 at the lower end of the 45 latter, in a manner illustrated to advantage in Figures 2 and 4 of the drawings. The other conduit 22 is in communication with an intake pipe 24, the latter extending downwardly from the bottom of a water tank 25. Consequently, 50 water passing from the tank 25 flows through the pipe 24 into the grate 21 and thence through the pipe 23 into the chute 13. The upper end of the chute 13 is in communication with a manifold 26 which in turn communicates with a return pipe 27 which latter leads to the upper end of the water tank 25. It is therefore apparent that the water, after 55 having passed through the grate 21 and chute 13 is returned to the tank 25 for recirculation through the grate and the chute. In this way there is a constant circulation of water 60 through the grate and chute. Not only does this circulation of water tend to effect drying 65 of the garbage, but in addition warping, dis-

tortion or premature deterioration of the grate or chute is also prevented.

The ash deflector 16 may be made of metal and is of cone shape to positively prevent adherence of the ashes to any part of the deflector. The deflector is provided at one side of its apex with an opening 28 which is directly above an endless conveyor belt 29 so that ashes gravitating from the deflector will be deposited directly on the belt and carried by the latter outside of the incinerator casing. It is of course to be understood that the conveyor belt may be operated in any desired manner and may be of any desired construction in order to effectively 75 transport the ashes.

The water tank 25 is provided with a supply pipe 30 which is equipped with a float operated valve in order to automatically close communication through the supply pipe 85 when the water has reached a predetermined level in the tank. Moreover, the tank is provided with an overflow pipe 31 in order to take care of excess water accumulating in the tank due to failure of the valve to operate or for any other reason.

Pivotaly mounted in the frame 12 of the incinerator opening is a plate 32 which may be made of metal and is of sufficient length to extend from the interior of the fire wall of the incinerator to the charging floor 8 of the housing 7. This plate serves as a slide or chute over which the wet garbage is passed for engagement with the water grate 21. It will be noted that when the plate 32 is in an operating position, as shown in Figure 2 of the drawings, the inner end thereof is positioned above the water grate to direct the garbage on to the latter. When in this position the plate 32 prevents the garbage from impinging against the chute 13 and correspondingly prevents depositing of the garbage on the grate 20. However, the plate 32 can be swung into the frame 12, thereby cutting off communication between the charging floor 8 and the water grate 21 and establishing communication between the charging floor and grate 20 by reason of the stationary chute 13.

In use of this device the wet garbage is deposited in the incinerator by passing the same through the opening of the housing 9 onto the plate 32. The garbage thus suspended on the water grate is permitted to dry out and as it is consumed the cremated residue gravitates downwardly into engagement with the grate 20 where complete cremation is effected and the ashes permitted to gravitate into the deflector 16. Where dry garbage is to be incinerated, the garbage passes directly from the charging floor 8 on to the chute 13 and from there on to the grate 20, where it is directly burned. In view of the fact that the inner end of the chute 13 of necessity is located in close proximity 115

to the grate 20, it has been found that in the absence of suitable means to cool the chute the latter is soon warped by the intense heat and thereby rendered unsuitable for use. By water jacketing the chute however, warping is prevented and effective functioning of the chute insured at all times.

It is of course to be understood that numerous changes may be made in this device, especially in the details of construction, proportion and arrangement of parts within the scope of the claim hereto appended. I am aware that the incinerator may be used independently of the housing such as designated 10 7 herein, and the garbage deposited directly on the chute. Where, however, the incinerator is arranged in proximity to a housing, into which the garbage is transported, it is desired to employ a fire door such as illustrated at 10 in the drawings, in order to prevent heat and products of combustion from entering the housing when the garbage is not 20 being deposited in the incinerator.

What is claimed is:—

25 A garbage incinerator including an incinerator equipped with superposed grates, a chute carried by the incinerator and leading to one of said grates, and means associated with said chute to close communication there- 30 through and establish communication with the other grate.

EDWARD M. OWENS.
